UNITED STATES PATENT OFFICE.

ARTHUR J. DONOVAN AND FRANK POKORNY, JR., OF NEW YORK, N. Y.

GOVERNOR FOR INTERNAL-COMBUSTION MOTORS.

1,290,122.

Specification of Letters Patent.

Patented Jan. 7, 1919.

Application filed December 29, 1917. Serial No. 209,477.

To all whom it may concern:

Be it known that ARTHUR J. DONOVAN and FRANK POKORNY, Jr., citizens of the United States, and residents of the borough of 5 Manhattan, in the city, county, and State of New York, have invented certain new and useful Improvements in Governors for Internal-Combustion Motors, of which the following is a specification.

10 This invention relates to internal combustion motors, and our improvements are directed to automatic governing means whereby the fuel passage is regulated by the piston speed so that while at determined 15 moderate speeds full charges are available as for heavy loads, the acceleration of piston speed functions to contract the fuel passage and thus limit the fuel supply until a balanced volumetric quota per piston stroke is 20 admitted to the manifold in normal restricted engine speed.

We are of course aware of the various types of governors, centrifugal and otherwise, found in the art, but the means devised 25 by us to control the motor, differ from these, and are based upon the idea of utilizing the vacuum or variable suction force created between the intake and carburetor, to actuate gravity return means for concomitantly 30 varying the volumetric flow of fuel, from a normal set supply, to accord with service conditions.

Other features and advantages of our said invention will hereinafter appear.

35 In the drawing:

Figure 1 is a vertical sectional view of our governing device.

Fig. 2 is a detail elevation of the free piston, and

40 Fig. 3 is a detail bottom plan view of the carrier for the cone.

In the example of our invention presented in this application we have shown it to comprise a gravity valve, cylindrical in form, 45 and functioning as a free piston under the suction influence of the motor piston, in aspirating the fuel charges, to automatically limit the capacity of the fuel passage.

Thus, let 1 indicate the intake manifold 50 of a motor, 2 the carburetor, and 3 an intermediate communicating member having flanges 4 and 5 to, respectively, connect said pipe with said manifold and carburetor.

55 The lower portion of member 3 which is a hollow cylinder 6, is bounded upwardly by an internal annular shoulder 7 from which

extends a sleeve 8. A free piston consisting of a tubular portion 9, slideable within sleeve 8, and a lower annular shoulder 10 that fits 60 slidably within cylinder 6, constitutes, with said cylinder, an annular chamber 11, whose capacity varies with the movement in and out of the free piston.

The chamber 11 is in communication with the atmosphere through an opening 12 in its 65 outer wall, this opening being composed, in the example, of intersecting holes drilled in cylinder 6 and shoulder 7. We have also shown an adjustable needle valve 13 as applied to said opening, for the purpose of 70 varying its capacity.

Also the tube 9 is apertured, as with holes 14, to co-act with opening 12 in providing an air passage through chamber 11 and into the fuel passage, of which the free piston, 75 being hollow, forms a component section. It will be noted that the chamber 11 is contractible through the upward movement of the free piston, until the shoulder 10 meets shoulder 7, and that said chamber is expandable through the downward movement of said piston.

Attention is also directed to the location of opening 12 in the upper portion of chamber 11, that it may function during the whole 85 of the free piston stroke and that the tube 9 is apertured vertically, for coördination of its apertured portion with opening 12 likewise throughout the stroke of the free piston.

It is our intention, in devising the parts 90 referred to and their relative arrangement, that the free piston shall be raised, varyingly, by, and according to the extent of the vacuum created through the suction strokes of the motor piston, whereby the fuel is 95 aspirated from the carburetor to the intake manifold.

In thus rising, the tubular portion 9 is intended to serve, in progressively restricting the passage taken by the fuel, to concomitantly diminish the volumetric supply thereof that is conveyed to the motor intake.

An example of means which co-act with 100 said tubular portion 9 in this operation will be described hereinafter.

It should be observed that the capacity of holes 14 exceeds the capacity of opening 12 when the latter is fully exposed, wherefore the exercise of suction pull through said holes 14 tends to exhaust the chamber 11 at 110 a greater rate than said chamber receives air through opening 12. Hence the suction

pull through the holes 14 creates a partial vacuum in said chamber, thus causing the chamber 11 to contract, which is effected in the upward movement of the free piston. 5 By means of the needle valve 13 the size of opening 12 may be varied and set to admit just the requisite quantity of air whereby the free piston may function with respect to a predetermined engine speed, bearing in 10 mind that the upper, tubular portion of said free piston is employed to vary the extent of the fuel passage.

In practice we have found that the holes 14 should vary dimensionally in progressive 15 manner, said holes increasing in size from the bottom of tubular portion 9 upwardly. This is for the reason that as the free piston ascends under the suction pull to which it is subjected, the chamber 11 decreases in its 20 cubical capacity, thereby responding to exhaustion at a lower vacuum pull, while it must also be borne in mind that, as the free piston ascends, so also the aspirating tension of the engine is increased through contraction of the fuel passage. 25

Mounted in the upper portion of member 3, axially over the free piston, is a depending cone 15, in spaced relation with the upper perimeter of tubular portion 9, said cone being supported by a spider or frame 16, having apertures 17 for the passage of the fuel which in the functioning of the engine is aspirated up from the carburetor, through tubular portion 9, around cone 15, and thence 30 through said apertures 17 to the intake manifold. The spacing between cone 15 and the perimeter of tubular portion 9, when the latter is seated in normal inoperative position, equals in area the full throat of the fuel 35 passage, and said spacing is contractible to closure in the upward movement of the free piston.

Means are however provided for varying the extent of the spacing between cone 15 and tubular portion 9, as follows: The said cone is mounted upon a threaded stem 18 for vertical adjustment. A vertical socket 19 is provided in the upper end of the cone, in which is seated a spring 20, supporting 50 a plunger or detent 21 which bears against a central plate 22 carried by spider 16, said plate having a concentric series of depressions 23 for the lodgment of detent 21, to thus retain the cone in a desired locked position of vertical adjustment. 55

By these or equivalent means the normal wide open extent of the fuel passage may be conveniently regulated and set.

The usual butterfly valve for throttling 60 the fuel may or may not be employed with a motor equipped with our invention.

In the operation of a motor having our improved governor, the free piston will rise to contract the fuel passage when the engine 65 speed exceeds the desired limit, and, then

exercising a throttling action, will fall again to a point leaving a clearance for which the inlet at 12 is set, and which will permit the engine to function normally at a predetermined speed. 70

When a heavier load is imposed upon the motor, causing it to slow down, this, by diminishing the suction pull, will permit the free piston to fall, thereby increasing the fuel passage, and enabling the motor, operating at a lower speed, to receive more fuel, until the motor picks up speed, which again causes the free piston to automatically contract the fuel passage. 75

Variations may be resorted to within the 80 spirit and scope of our said invention and parts thereof used without others.

We claim:—

1. The method of governing the speed of internal combustion motors, which consists 85 in varying the volumetric capacity of the fuel passage through the force created by the motor in its aspiratory operation, as opposed to gravity.

2. The method of governing the speed of 90 internal combustion motors, which consists in controlling the fuel supply in its passage to the motor intake by varying the volumetric capacity of the passage through the force created by the motor in its aspiratory opera- 95

tion, as opposed to gravity. 3. Speed regulating means for internal combustion motors, comprising a gravity return fuel-control valve, and means enabling the fuel aspirating force to also apply 100 to the operation of said valve in governing the volumetric capacity of the passage.

4. In an internal combustion motor having a carburetor and an intermediate fuel passage, the combination of a gravity return 105 fuel control valve, and means, governed through the character of the vacuum created by variable motor speed, to actuate said valve in governing the volumetric capacity of the fuel passage. 110

5. In an internal combustion motor having a carburetor and an intermediate fuel passage, a free, gravity return piston comprising a throttle, and means actuated by the aspirating force of the motor, to operate 115 said piston, whereby the volumetric capacity of the fuel passage is governed.

6. In an internal combustion motor having a carburetor and an intermediate fuel passage, the combination of a hollow, gravity return free piston, included in said passage, said piston functioning as a fuel throttle, a chamber in which said piston works, an air inlet to said chamber, and means of communication between said chamber and passage, whereby the fuel raising, suction pull also serves to operate said piston. 120

7. In an internal combustion motor having a carburetor and an intermediate fuel passage, the combination of a hollow, grav- 130

ity return free piston included in said passage, an inverted cone co-acting axially with said piston as a fuel throttle, means of vertical adjustment for said cone, and means actuated by the aspiratory force of the motor, to operate said piston, whereby the volumetric capacity of the fuel passage is governed.

8. A governor for internal combustion
10 motors comprising a passage connecting the carbureter and motor intake, a gravity return free piston within said passage operable by the suction pull of the motor, and means co-acting with said piston, to vary the volumetric fuel capacity of said passage.

9. A governor for internal combustion

motors comprising a passage connecting the carbureter and motor intake, a stationary throttle member near the upper portion of said passage, and a gravity return, free piston operable by the suction pull of the motor, to approach said member and thereby vary the volumetric fuel delivery from said passage.

Signed at the borough of Manhattan in 25
the city, county and State of New York this
26th day of December A. D. 1917.
